A. A. JONES,

TIMER

APPLICATION FILED MAR. 28, 1921.

1,410,317.

Patented Mar. 21, 1922.

Alva A. Jones. INVENTOR.

Watson E. Coleman ATTORNEY.

UNITED STATES PATENT OFFICE.

ALVA A. JONES, OF SHELBYVILLE, ILLINOIS.

TIMER.

1,410,317.

Specification of Letters Patent. Patented Mar. 21, 1922.

Application filed March 28, 1921. Serial No. 456,429.

To all whom it may concern:

Be it known that I, ALVA A. JONES, a citizen of the United States, residing at Shelbyville, in the county of Shelby and State of Illinois, have invented certain new and useful Improvements in Timers, of which the following is a specification, reference being had to the accompanying drawings.

10 This invention relates to improvements in timers and more particularly to a distributor and breaker, especially adapted for use in ignition systems of the type at present used in the Ford automobile.

15 A further object of the invention is to provide a device of this character which permits of the enclosure of the spark plug connections in conduits in order that they may be fully protected from grease, oil, water 20 and the like.

A further object of the invention is to provide a device of this character which may be readily adjusted.

Other objects and advantages of the invention will become apparent throughout the course of the following description:

In the accompanying drawings, wherein for the purpose of illustration is shown a preferred embodiment of my invention, and 30 wherein like reference characters designate like parts throughout,

Figure 1 is a sectional view taken through a distributor and breaker constructed in accordance with my invention,

35 Figure 2 is a plan view of my device, the breaker cap being removed,

Figure 3 is a transverse sectional view taken through the cap on the line 3—3 of Figure 4, and

40 Figure 4 is a section on the line 4—4 of Figure 1.

Referring now more particularly to the drawings, the numeral 10 indicates a stationary distributor block provided with a 45 central opening through which the timer shaft 11 rotatably extends. The distributor block is provided with a circular cup-shaped depression in its face, the side wall 12 of which is co-axial with the timer shaft and 50 which side wall has imbedded therein segments 13 connected by suitable wiring with the spark plugs of the engine. The base of the recess has imbedded therein an annular collector ring 14.

55 The numeral 15 indicates a shaft having one end bored out for the reception of the

timer shaft 11, the shaft 15 being held for rotation with the timer shaft by means of the usual key. The tubular shaft 15 has moulded thereon a distributor brush 16 of 60 some suitable material such as bakelite. This brush has mounted therein a carbon contact brush 17 which abuts the annular collector ring 14 and which is electrically connected with a strip of metal 18 which 65 extends downwardly upon the end of the distributor brush 16 and is spaced from the wall 12 of the recess and the contact segments 13 imbedded therein, a distance of approximately one sixty-fourth of an inch. 70

The numeral 19 indicates a cap forming a closure for the cup-shaped recess of the distributor block which is provided with an upward extension 20 forming a housing, against the upper wall of which housing the 75 usual cap retainer 21 engages. The cap 19 is provided with a shifter arm 22 (see Figure 4) to which the usual timer control arm may be secured.

The shaft 15 is provided with a reduced 80 squared extension forming a cam 23 extending into the housing 20, and a further reduced portion 24 circular in cross section which engages in a suitable bearing 25 formed in the outer wall of the housing so 85 as to assure proper positioning of the cap with respect to the shaft. The side wall of the housing 20 has secured thereto a threaded block 26 through which is directed a contact screw 27 which is adapted to coact with 90 and is normally engaged by a contact 28 mounted upon a spring 29 secured within the housing and grounded in any suitable manner as indicated. This spring is provided with a bearing face 30 to be engaged 95 by the corners of the squared portion 23 of the shaft 15 and when so engaged is separated from the contact screw 27 to break the circuit. The contact screw 27 may be held in adjusted position by a lock nut 31, 100 and this contact screw forms a binding post for the reception of a lead from the source of current and passing through the primary of a coil. The secondary of the coil will be connected to the collector ring 14 of the distributor block 10, and as hereinbefore stated, 105 the segments 13 of the distributor block will be directly connected with the spark plugs.

In the operation of my device the corners of the squared portion of the shaft 15 are 110 so synchronized with the brush 16 that they cause a separation of the contacts 27 and 28

as the collector brush is alined with the corresponding segment. Accordingly the primary circuit is broken and an impulse is sent to the secondary coil to the collector 5 ring 14, brush 17, strip 18, segment 13, to the spark plug. Attention is particularly directed to the fact that the mounting of the supplementary shaft 15 upon the end of the timer shaft in the manner shown permits 10 ready removal of this supplementary shaft so that it may be inserted in the cap while the cap is removed, and the action of the contacts 27 and 28 accurately determined.

As many changes are possible in the shape, 15 size and arrangement of the various parts hereinbefore set forth without materially departing from the spirit thereof, I do not limit myself to the specific structure hereinabove set forth except as hereinafter 20 claimed.

What I claim is:

1. In a distributor and breaker, a stationary distributor block of insulating material having a cup shaped recess formed therein, 25 spaced segments imbedded in the side walls of said recess, a member rotatable within the recess and embodying a distributor brush coacting with said segments, a cap for said recess, a pair of contacts carried by 30 said cap one of which is spring pressed for engagement with the other, and an extension of said rotatable element insulated from the brush of said rotatable element, embodying portions corresponding in number and arrangement to the segments of said distributor cap adapted to shift said spring pressed 35 contact against the action of the spring thereof.

2. In a distributor and breaker, a stationary distributor block of insulating material having a cup shaped recess formed therein, spaced segments imbedded in the side walls of said recess, a member rotatable within the recess and embodying a distributor brush 40 coacting with said segments, a cap for said recess, a pair of contacts carried by said cap

one of which is spring pressed for engagement with the other, and an extension of said rotatable element insulated from the brush of said rotatable element, embodying portions corresponding in number and arrangement to the segments of said distributor cap adapted to shift said spring pressed contact against the action of the spring thereof, the other of said contacts being longitudinally adjustable, said rotatable element being readily removable and embodying a further portion rotatably engaging in a bearing formed in said cap. 50 55

3. In a distributor and breaker, a stationary distributor block of insulating material having a cup shaped recess formed therein, spaced segments imbedded in the side walls of said recess, a collector ring mounted in the bottom of said recess, a member rotatable 60 within the recess and embodying a collector brush coacting with the segments, a cap for said recess, an extension of said rotatable element embodying a portion engaging said cap, and a breaker mechanism operated by 65 said extension.

4. In a distributor and breaker, a stationary distributor block embodying spaced segments, a rotatable shaft extending into said distributor block, a second shaft embodying 75 a bore receiving the first named shaft, said second named shaft being secured against rotation with relation to the first named shaft, a distributor brush carried by the second named shaft coacting with said segments, a shiftable cap for said distributor block embodying a bearing receiving an end portion of the second named shaft, a pair of contacts carried by said cap one of which is spring pressed for engagement with the 80 other, and a contact engaging portion formed on said second named shaft and engaging said spring contact to cause the separation of the contacts. 85

In testimony whereof I hereunto affix my 90 signature.

ALVA A. JONES.
